UNITED STATES PATENT OFFICE.

JOHN ALBERT SWINDELL AND JOHN C. SWINDELL, OF PITTSBURGH, PENNSYLVANIA.

ANNEALING-FURNACE.

1,112,237.

Specification of Letters Patent.

Patented Sept. 29, 1914.

Application filed December 12, 1913. Serial No. 306,225.

To all whom it may concern:

Be it known that we, JOHN A. SWINDELL and JOHN C. SWINDELL, both citizens of the United States, and both residing at Pittsburgh, in the county of Allegheny and State of Pennsylvania, have invented a new and useful Improvement in Annealing-Furnaces, of which the following is a full, clear, and exact description, reference being had 10 to the accompanying drawings, forming part of this specification, in which—

Figure 1 is a sectional perspective view of one form of furnace embodying our invention; Fig. 2 is a transverse vertical section of another form of furnace embodying our invention; and Figs. 3 and 4 are horizontal sections, taken respectively on the lines III—III and IV—IV of Figs. 1 and 2.

Our invention has relation to annealing 20 furnaces, and more particularly to furnaces of the general character described and claimed in the patent to William A. and John C. Swindell, No. 624,401 of May 2, 1899.

25 The object of the present invention is to provide a furnace which will possess the well known advantages of furnaces constructed in accordance with the said patent and which have gone into extensive commercial use, 30 together with added advantages which still further increase the efficiency of the furnace.

An especial object of the invention is to provide for a better and more efficient combustion of the fuel gas by providing means 35 of novel character and arrangement whereby the air and gas in passing to the point of combustion are preheated to a high degree.

In the accompanying drawings, we have 40 shown our invention as applied to two different forms of furnaces in which the combustion takes place at the central portion of the furnace and the flames and products of combustion pass laterally in opposite directions toward the sides of the annealing 45 chamber and over a row of annealing boxes placed at each side of said chamber. After passing over the annealing boxes, the products of combustion pass downwardly into 50 longitudinally arranged waste flues which carry them to the stack. These waste flues, together with the air and gas supply flues, are all arranged longitudinally in the base 55 of the furnace and in such a manner that the air and gas become preheated to a very great extent before meeting. This general

arrangement is not, however, claimed in the present case, but forms the subject matter of a co-pending application by John Albert Swindell, one of the applicants herein. The 60 novel subject matter of the present application has a reference to a further preheating of the air and gas.

Referring to the accompanying drawings and first to the construction of furnace shown in Figs. 1 and 3, the numeral 2 designates the wall of the furnace having the base 3 and inclosing above said base portion an annealing chamber 4. This annealing chamber is provided at each side of the center with a suitable supporting surface 5 for the usual annealing boxes which are placed end to end. Formed in the base 3 of the furnace are the longitudinally extending waste flues 6 and 6^a, the longitudinally extending 70 air flues 7, and the central longitudinally extending gas supply flue 8. The waste and air flues are duplicated for each side of the furnace. The waste flues are shown as double-pass flues (see Fig. 3), the two passes 75 6 and 6^a of each flue being connected at one end as shown. Each air flue 7 is arranged between the two passes of a waste flue; and the central gas flue 8 is arranged between the passes 6^a of the two waste flues. Inasmuch 80 as these furnaces are operated at relatively high temperatures for considerable periods of time, the entire base of the furnace becomes highly heated, not only by conduction 85 through the base from the annealing chamber, but also by conduction through the walls of the waste flues. The waste gases passing to the stack are at a comparatively high temperature and a large amount of heat is thus available for conduction through these 90 walls. This conduction readily takes place owing to the fact that the walls of the air flues are being constantly cooled by the entrance of air at atmospheric temperature. It will therefore be apparent that both the 95 air and the gas will be preheated to a very considerable degree in passing through these flues.

The two parts of the annealing chamber are separated at their lower portions by a 100 central longitudinal wall 9. In accordance with our present invention, this wall is made hollow to inclose and contain a central longitudinal air preheating chamber 10 extending down into the base 3 immediately above 105 the roof arch of the gas flue 8. The air flues 7 communicate with this chamber 10 by

a series of oblique transverse ports 11. The upper portion of the chamber 10 has at each side a series of discharge openings 12. We also provide the central portion of the furnace with the baffle walls 13, one at each side of the central wall 9. The upper edges of the baffle walls terminate at about the level of the bottoms of the discharge openings 12. Extending upwardly from the gas flue 8 are 10 two series of vertical ports 14 and 15, these ports leading to the continuous chambers 14^a and 15^a which extend to the upper edges of the said baffle walls and are arranged to discharge gas adjacent to the openings 12. The 15 two series of ports 14 and 15 are in staggered relation to each other; and the two sets of air ports 11 are also staggered so that there is an alternating arrangement of gas and air ports at each side.

20 It will be readily understood that the walls of the central chamber 10 will become highly heated in the operation of the furnace, and that thereby the air delivered into such chamber by the ports 11 will also be 25 raised to a comparatively high temperature. The gas flowing upwardly through the ports 14 and 15 also has its temperature increased. Therefore, when the air and gas meet adjacent to the upper edges of the baffles 13, 30 both air and gas are at relatively high temperatures and a very high degree of combustion takes place.

In Figs. 2 and 4 we have shown our invention applied in a somewhat modified form 35 and to a somewhat differently arranged furnace. In this furnace each waste flue 16 is a single-pass flue and each air flue has the double passes 17 and 17^a, the air first entering the pass 17 of each flue and then going 40 into the pass 17^a. 18 is the central gas supply flue. Each pass 17^a of the air flues communicates with the chamber 19 in the central wall 20 by means of the ports 21 which correspond to the ports 11 of the furnace 45 first described. The gas flue 18 communicates with this central chamber 19 by a series of vertical ports 22. The upper portion of the side walls of the chamber 19 are provided with the discharge perforations 23 50 preferably arranged at different levels and discharging into chambers 24 behind the longitudinal baffle walls 25. In this form it will be seen that the air and gas are brought together in the chamber 19, but with substantially the same degree of preheating as in 55 the form first described. Not only are the walls of the chamber 20 at a very high temperature, but the baffle walls 25 are also, of course, at a high temperature, so that combustion takes place under the most favorable 60 conditions.

In both forms of furnace shown and described, the chamber 4 is, in effect, divided into two chambers or compartments; and 65 each chamber or compartment may be op-

erated independently to or at a different temperature from the other chamber or compartment. The wall at that side of each chamber or compartment which has the inlet ports may be of any desired height.

70 It will be readily understood that our invention is not limited in its application to furnaces of the general construction and arrangement of air, gas and waste flues such as shown and described. In all cases, however, 75 we prefer to employ our invention in connection with a longitudinal parallel arrangement of such flues located in the base of the furnace in such a manner that the gas and air will be preheated in passing through it 80 and can be readily brought together at the central portion of the furnace where further preheating in accordance with our invention takes place prior to and at the time of combustion.

85 By the term "preheating chamber" as used in the claims, we desire to cover either an air chamber, such as the chamber 10 of Fig. 1, or a combined air and gas chamber, such as that shown at 20 in Fig. 2.

90 While our invention is particularly applicable to annealing furnaces it may also be applied to other heating furnaces.

95 What we claim is:

1. A furnace of the character described 95 having longitudinally extending gas and air supply flues in its base and having a centrally arranged longitudinal preheating chamber extending downwardly within the base of the furnace, and with which said air 100 flue communicates, said chamber having discharge openings at its upper portion, and means for delivering gas from the gas supply flue to be mixed and burned with said air; substantially as described.

105 2. A furnace of the character described having a hollow central wall extending upwardly within the lower portion of the furnace chamber and containing therein a preheating chamber, said wall having discharge openings leading outwardly therefrom into said chamber, means for delivering air into the said preheating chamber, and means for supplying gas to be burned with said air, said means comprising a flue 110 extending longitudinally within the base of the furnace below the said wall, and having upwardly extending ports, and said furnace chamber having offtake means for the products of combustion extending along its opposite side throughout substantially the entire length thereof.

115 3. A furnace of the character described having a hollow central longitudinal wall projecting upwardly into the lower portion 120 of its furnace chamber, said wall inclosing a preheating chamber having openings leading outwardly therefrom into the furnace chamber, a longitudinally extending baffle wall adjacent to said hollow central wall, 125

means for delivering air into the said pre-heating chamber, and means for supplying gas to be burned with the air preheated in said preheating chamber; substantially as 5 described.

4. A furnace of the character described having in its base longitudinally arranged waste ports communicating with the opposite sides of the furnace chamber and also 10 having in its base longitudinally arranged air and gas supply ports whose walls are arranged to be heated by conduction from the waste ports, said furnace also having a centrally arranged preheating chamber communicating with the air flues and having 15 discharge openings at opposite sides of its upper portion within the furnace chamber, and connections leading from the gas port to supply gas to be burned with the air pre-heated in said chamber; substantially as described.

5. A furnace of the character described having its base provided with waste, air and gas ports, the walls of the air and gas 20 ports being arranged to be heated by conduction from the furnace chamber and also 25

by conduction from the waste ports, and also having at its central portion air and gas heating passages connected respectively with the said air and gas ports; substantially as 30 described.

6. A furnace of the character described, having a heating chamber or compartment with a hollow wall at the lower portion of one side thereof, said wall containing a pre-heating chamber, the base of the furnace having therein a longitudinally extending air flue which is connected with said pre-heating chamber, and the latter having outlets into the heating chamber or compartment, a longitudinally extending baffle wall adjacent to said hollow wall but spaced laterally therefrom, and means for supplying gas to be burned with the air; substantially 35 40 45 as described.

In testimony whereof, we have hereunto set our hands.

JOHN ALBERT SWINDELL.
JOHN C. SWINDELL.
